(57) **CLAIM**

The ornamental design for a spray valve face plate, as shown and described.

DESCRIPTION

FIG. 1 illustrates the front of the spray valve face plate from an elevated perspective view.

FIG. 2 illustrates the back of the spray valve face plate from an elevated perspective view.

FIG. 3 illustrates the front of the spray valve face plate from an elevation view.

FIG. 4 illustrates the back of the spray valve face plate from an elevation view.

FIG. 5 illustrates the left side of the spray valve face plate from an elevation view.

FIG. 6 illustrates the right side of the spray valve face plate from an elevation view.

FIG. 7 illustrates the top of the spray valve face plate from a plan view; and,

FIG. 8 illustrates the bottom of the spray valve face plate from a plan view.
